UNITED STATES PATENT OFFICE.

BURT H. MACY, OF SOMERVILLE, MASSACHUSETTS.

ELEVATOR SAFETY-LOCK.

1,270,853.

Specification of Letters Patent.

Patented July 2, 1918.

Application filed March 18, 1915. Serial No. 15,242.

To all whom it may concern:

Be it known that I, BURT H. MACY, a citizen of the United States, and resident of Somerville, in the county of Middlesex and 5 State of Massachusetts, have invented certain new and useful Improvements in Elevator Safety-Locks, of which the following is a specification.

The present invention relates to a lock 10 adapted to be used in connection with an elevator of which the operation is controlled by a shipper cable, to prevent movement of the shipper cable under certain conditions. The invention consists in a novel construction 15 of such lock and in the combination of such lock with the shipper cable of an elevator and with mechanism operable by a gate in the elevator well for opening and closing the lock. In the drawings I have 20 shown a form of my invention and the association of the same with operating mechanism in a combination which also forms a part of the invention.

Figure 1 is a plan view of the elevator 25 lock and of the operating mechanism with which it is associated.

Fig. 2 is an elevation of the lock and such mechanism.

Fig. 3 is a sectional view on a larger scale 30 of the lock taken on line 3—3 of Fig. 1, looking in the direction of the arrows.

Fig. 4 is a horizontal sectional view of the lock.

The same reference characters indicate the 35 same parts in all the figures.

I will first describe the lock and then explain the combination in which it is used as here shown. The exterior of the lock is a casing composed of two separable parts 10 and 12, each of said parts being preferably a single casting and being formed as an oblong box-like structure open at one end. The parts 10 and 12 have lugs 11 and 13, respectively, adjacent to their open ends 40 which receive attaching screws 14, whereby said parts are connected to form a substantially continuous casing inclosing an inner space which is open throughout the length, width and thickness of the entire casing. 45 The top and bottom sides of the casing members at their contiguous open ends are recessed, such recesses forming together a substantially circular opening 15, surrounded by flaring lips 16, 17 on the respective parts of 50

the casing. These lips form guides to the 55 opening 15.

The shipper cable 18, by which the operation of the elevator car is controlled, and knobs or abutments 19, 20 on such cable, are adapted to pass through the opening 15 in 60 the casing of the lock and the knobs are guided into such opening when the cable is moved endwise, by the bell-mouthed guide formed by the lips 16, 17 surrounding such opening. The knobs 19 and 20 are separated, as usual, by a space sufficiently wide 65 to admit the jaws of the lock.

In the casing are mounted the locking jaws 21 and 22 which are disposed on respectively opposite sides of the cable 18. 70 Jaw 21 is mounted on a slide 23, which has a tail piece 24, and the jaw 22 is mounted on a slide 25 between the jaw 21 and the tail piece 24. These slides fit between the walls of the casing in such a manner that 75 they are maintained in proper relation to each other, and at the same time are enabled to slide freely. It will be observed in Fig. 4 that each slide extends across substantially the entire width of the interior of the casing. A spring 26 is interposed between the tail piece 24 and the slide 25 normally holding the slides in the position shown in Fig. 4, where the tail piece abuts against the back end of the casing and the slide 25 is 80 pushed away from that end of the casing to the limit of its movement. In this position of the parts, jaw 21 partly crosses the opening 16 and enters the space between the knobs 19 and 20 on the shipper cable, and 85 the adjacent edge of the jaw 22 occupies a similar position at the opposite side of the cable. The adjacent sides of the jaws are recessed to give ample space for the cable but the recess is narrower than the width 90 of the knobs 19 and 20. The two jaws come into contact at 27, at which point the movement of the slide 25 is arrested by the jaw 21. Preferably the jaw 22 is formed to overlap the slide 23, and is slotted at its end, 100 the slot admitting a narrow neck 28 on the slide 23. In other words, a portion 28 of the slide is made narrower than the rest of the slide, and the jaw 22 is provided with two ears 29, which lie on opposite sides of 105 the narrow portion 28, as shown in Fig. 3. I do not limit the invention to this feature however. The slide 25 has a notch 30 and

the slide 23 a notch 31, and these notches are entered by the arms 32 and 33, respectively, of a lever which is mounted in the casing between the slides, as shown in Fig. 4, and is provided with a shank 34, which passes through the top and bottom walls of the casing and carries an operating handle 35. It will be apparent that turning the handle 35 in the only direction possible will 10 swing the operating lever and shift the jaws in relatively opposite directions. The bearings of the shank 34 in the walls of the casing form the pivot axis and fulcrum of the lever, whereby the jaws 21 and 22 are caused to move equally and oppositely. When the handle is released, spring 26 restores the jaws and operating lever to their normal position, which is their locking position. It will be apparent also that the 20 lever is operable to transmit movement from one of the slides to the other, so that when the force is applied by any means to either jaw tending to move the same into the open position, the other jaw is oppositely moved at the same time toward its open position. The lever is thus not only an actuator for the jaws but is at the same time a transmission means for transmitting movement from either jaw or slide to the other. A 30 particularly noteworthy mechanical feature of the lever resides in the rounded formation of its extremities and the complementary formation of the recesses in the slides, such formation being of practical importance in that it enables the parts to be assembled without fitting or finishing the contacting surfaces between the lever and slides, and that when assembled the parts are adapted to move in the designated manner smoothly 35 and with low frictional resistance.

The jaws are at all times free to be separated by pressure applied to them through the knob 19 or the knob 20. Each of these knobs is tapered at one end, as usual, the tapered end being enough narrower than the recess between the jaws to enter such space, and when either knob is thus moved into the space between the jaws it wedges them apart against the pressure of spring 26, 40 until its square end passes the jaws, when the latter spring together into the space between the two knobs.

The lock which I have above described is well adapted to be used in connection with 55 the door or gate to an elevator well for preventing operation of the shipper cable to start the elevator car when the gate is open. To this end the lock is mounted by a bracket 36 on the wall of the elevator well in a position such that the return line of the shipper cable 18 may pass through it. The lock is 60 then operable by the door or gate of the well through the following mechanism:—a rod or link 37 is connected by a pivot pin, 38 65 with the handle 35, and is adapted to slide

endwise through supports 39, 40. It carries a tappet or abutment 41. A rock shaft 42 is mounted in bearings 43 and 44, and carries a tappet or wiper 45 which is arranged to bear on the abutment 41 of the link. The rock 70 shaft 42 also carries an arm 46 which projects into the path of a lug or pin 47, shown dotted in Fig. 1, carried by the gate or door 48 to the opening of the elevator well. The particular arrangement shown is designed 75 for an elevator installation in which the gates slide vertically and are raised when open, but the mechanism may be modified for application to installations in which the gates or doors move in other ways. When 80 the gate is raised the mechanism occupies the position shown in the drawings, and when the gate descends it rocks the shaft 42, thereby causing the tappet 45 to bear on the abutment 41 and move the link 37 so as to swing 85 the arm 46 and rock the operating lever 32, 33 in the manner required to separate the jaws. On raising the gate again the pressure acting on arm 46 is relieved and the spring 26 is enabled to close the jaws and 90 restore the parts to the position shown. Of course other springs may be provided, if desired, at any convenient points to reinforce the action of the spring 26, without departing 95 from the invention.

I propose to provide a lock and an operating mechanism having the essential characteristics above described at each of the floors through which the elevator passes, so that when the door or gate at any floor is 100 opened, the car can not be started. The shipper cable of course is provided with a pair of knobs adjacent to each of the safety locks, and these knobs are so placed that they are on respectively opposite sides of the lock jaws when the cable is in the neutral position, that is, the position for stopping the car. The cable can not be moved out of this position unless the jaws of all the locks are open, and this condition can obtain only 110 when all of the gates are closed. The cable may be brought into the neutral position from either displaced, or running, position whether the lock jaws are open or closed on account of the tapered formation of the 115 knobs.

The lock which I have above described is simple and efficient, consisting of but few parts which can be made amply strong without causing the lock as a whole to be too 120 bulky or too heavy. It is positive in action and practically incapable of getting out of order. The form and arrangement of the movable parts enables the casing to be made of such construction that it can be opened 125 to admit the shipper cable between the jaws without disarranging the mechanism of the lock. The slides and levers are wholly supported in and by the part 10 of the casing, the part 12 being merely a cover to inclose 130

- the projecting part of jaw 21, and the mechanism is complete and operative whether the casing member 12 is in place or not. Some forms of lock heretofore made require, in 5 order to be associated with an elevator shipper cable, either that the shipper cable be disconnected and threaded through the lock, or the lock be disassembled and reassembled about the cable, there being no other way to 10 pass the cable between the jaws of the lock. With my construction it is merely necessary to remove the casing part 12, draw the jaws apart and slip the cable between them and then replace the cover 12.
- 15 When this lock is used in the manner above described the elevator car may also, if desired, be equipped with an additional lock of the same construction or of any other construction. The combination in which the 20 present lock is used as above described, is additional to any lock which may be mounted upon the car, and provides an additional safeguard which prevents the car from being started when any gate is open, even though 25 all other conditions may be favorable. As the lock here described is arranged in connection with the return stretch of the shipper cable, which passes outside of the elevator car, the lock may be located in any 30 position between the limits of movement of the car without interfering with such movement, and I am therefore able to mount such a lock at each floor, as already stated.
- In definition of the terms used in the 35 claims, the gate or door, previously described, may be considered as generically a guard for the opening to the elevator well, whatever specific form it may have, whether it be a gate so-called or a door so-called.
- 40 The parts which have been called knobs 19 and 20 are in function and effect stops, which may have other forms than those shown, provided they perform the function of preventing movement of the shipper cable when 45 the lock is in the way of stops.
- What I claim and desire to secure by Letters Patent is:
1. In an elevator installation, the combination with a shipper cable and separated 50 stops on said cable, of a lock mounted in a stationary location and having relatively movable separable jaws embracing said cable and adapted to occupy a position between said stops in the path thereof, whereby to 55 prevent movement of the cable into the position for starting the car, an actuator for said jaws, an endwise movable rod connected to said actuator and having a tappet, and a rock shaft having a plurality of arms one of 60 which is arranged to engage said tappet and the other is arranged to be engaged and moved by an elevator gate.
  2. In an elevator installation, the combination with the return stretch of a shipper 65 cable, of locks mounted adjacent to each of
- the floors or stages of said installation, each lock being provided with relatively movable jaws embracing the cable, a pair of separated stops on the cable adjacent to each of the several locks, the stops of each pair being 70 disposed on opposite sides of said jaws when the cable is in the neutral position, and the jaws normally in position to interfere with said stops, a gate or guard at each stage of the installation, an operating lever engaged 75 with both jaws and arranged for operation to move the jaws apart, and mechanism through which each gate is adapted to turn the operating lever of the lock at the same stage in the manner which causes the jaws 80 of that lock to be separated, or opened.
3. In an elevator installation, the combination with a lock having separable jaws and an operating lever engaged with said jaws, of an arm connected with said lever, 85 a link joined to said arm and having an abutment, and a rock shaft having a tappet arranged to bear on said abutment and having an arm adapted to be moved by pressure applied thereto.
4. An elevator lock comprising a casing 90 having guideways at opposite sides thereof, slides movable in said guideways each having a jaw element projecting toward the opposite guideway, said jaws passing one 95 another and formed with a space between them adapted to admit an elevator shipper rope, said slides each having on the side toward the other a socket, and a lever pivoted in the casing between said slides having 100 arms entering said sockets whereby said lever is operable to move said slides simultaneously in relatively opposite directions and also to transmit movement from one slide to the other.
5. An elevator lock comprising a casing 105 having guideways at opposite sides thereof, slides movable in said guideways each having a jaw element projecting toward the opposite guideway, said jaws passing one 110 another and formed with a space between them adapted to admit an elevator shipper rope, said slides each having on the side toward the other a socket, and a lever pivoted in the casing between said slides having 115 arms entering said sockets whereby said lever is operable to move said slides simultaneously in relatively opposite directions and also to transmit movement from one slide to the other and a spring engaged with 120 said slide so as to press upon one and react against the other in a manner tending to place and retain said slides in the positions where their jaws are nearest to one another.
6. An elevator lock comprising two slides 125 mounted to move in parallel paths and having a space between them, each slide having a jaw extending toward the location in which the other slide moves, and one of said slides having a tail piece crossing the line 130

of movement of the other slide, a spring interposed between the said tail piece and said other slide, and a lever interposed between the two slides and having an arm in connection with each:

7. An elevator lock comprising two slides mounted to move in parallel paths and having a space between them, each slide having a jaw extending toward the location in 10 which the other slide moves, said jaws passing one another, and each slide having a

curved concaved recess in the side facing toward the other slide, and a lever pivoted between said slides having arms with rounded ends entering the recesses of the respective slides.

In testimony whereof I have affixed my signature in presence of two witnesses:

BURT H. MACY.
